H. VARDER.

TRAIN BUMPER.

APPLICATION FILED JUNE 24, 1920.

Patented Feb. 8, 1921.

UNITED STATES PATENT OFFICE.

HOLGER VARDER, OF NEW YORK, N. Y.

TRAIN-BUMPER.

1,368,002.

Specification of Letters Patent.

Patented Feb. 8, 1921.

Application filed June 24, 1920. Serial No. 391,392.

To all whom it may concern:

Be it known that I, HOLGER VARDER, a citizen of the United States, residing at borough of Manhattan, city of New York, in the 5 county of New York and State of New York, have invented certain new and useful Improvements in Train-Bumpers, of which the following is a specification.

This invention relates to improvements 10 in train bumpers for use in terminals, or on sidings, or in similar locations, where it is desired to bring a car, or train of cars, to a stand-still in a short distance without a sudden shock or the danger of the cars leaving the track. This improved bumper is 15 designed to stop a moving train within a distance of a few feet and without causing damage to either the train or bumper, and the result is accomplished by frictional resistance which is brought into opposition to 20 the movement of the train.

One of the objects of the invention is to provide a frictional bumper which primarily gradually increases the frictional resistance as it starts to move backward under the pressure of the train, and a further object is to provide an efficient bumper of this type of simple construction and at the same time a substantial structure.

These and other objects hereinafter set forth, are attained by the means illustrated in the accompanying drawing, in which:

Figure 1 is a longitudinal sectional view of the device taken on the line 1—1 of 35 Fig. 2.

Fig. 2 is a view on the line 2—2 of Fig. 1.

Fig. 3 is a view similar to Fig. 1 showing the brake-shoe in an operating position and also illustrating a modified form of supporting base.

Fig. 4 is a detail view showing a modified form of supporting means for the brake-shoe, and

Fig. 5 is a detail sectional view showing a 45 plan view of one of the friction plates.

Similar reference numerals in all of the figures of the drawing designate like parts.

Referring to Figs. 1 and 2 of the drawing, 50 5 designates a supporting beam having its rear end embedded in a concrete wall 6, and whose front end is fastened by bolts 6' to a plurality of anchor-plates 7, the ends of which are secured in concrete piers 8 extending forwardly from the wall 6, and said 55 anchor-plates extend across the space between the piers and beneath the supporting

beam 5 which is positioned longitudinally in said space.

Mounted to travel along the supporting beam 5 is a brake-shoe 9 which is formed 60 with depending side arms 10 connected at their top ends by a bracket 11, and connected at their bottom by a suitable connection 12 which forms a housing for springs 29. Adjacent the rear edge of the shoe is suitably mounted in the bracket 11 a supporting-roller 15 that is adapted to engage the upper surface of the supporting beam 5. 65

Secured to the underside of the supporting beam 5 are the friction bars 16, the 70 front ends of which are interposed between the anchor plates 7, and their rear ends are secured to the beam 5 by the bolts 17 in a manner to space the bars apart and permit a slight vertical movement relative to each 75 other and to the bottom of the supporting beam.

Positioned between the friction bars 16 are the friction plates 18, which are substantially equal in width to the bars 16, and 80 are provided preferably at their rear ends, with side projections 19 that are adapted to extend through openings 20 formed through the sides 10 of the brake-shoe.

Secured to the bottom of the brake-shoe is 85 an extension 21 to which is secured one end of the springs 23 whose front ends are secured to angle-bars 24 suitably and rigidly fixed to the piers 8 and extending across the space between the piers. These springs 90 form an initial resisting force to the movement of the brake shoe, so that, when the force of a moving body is applied to the brake-shoe above the friction members a tilting movement is caused to the brake-shoe, which in turn causes the friction members to tightly engage each other in proportion to the force applied by the springs 29. 95

The force from the moving train is applied through the boom 25 which is preferably formed of two U-shaped beams positioned with their open sides next to the supporting beam 5 and connected at their front ends by a cap or buffer head 26 against which the moving train pushes. The boom is supported by, and guided in a horizontal plane by guide-rollers 27 which are pivoted to the supporting beam 5, and the force applied to the boom is transmitted to brake-shoe by the engagement of the rear end of the boom with 100 abutments 28 rigidly supported by the side arms 10. The engagement between these 110

abutments 28 and the end of the boom is a contact engagement, so that the tendency of the force applied is to move the brake-shoe from its normal slightly inclined position, 5 as shown in Fig. 1, to a vertical position as shown in Fig. 3, thereby pressing the springs 29 against the friction plates. In the normally slightly inclined position of the brake-shoe the friction-plates 18 are in relatively 10 loose engagement with the friction-bars 16, so that they can slide easily thereover, but when the brake-shoe is caused to move in the direction of its vertical position, the friction-plates and bars are forced into relatively 15 tight engagement in proportion to the amount of force applied by the compression of the springs 29, thereby creating sufficient friction to retard the movement of the train.

It will readily be seen that the pressure 20 from the springs 29 on the friction-plates is constant depending on the compression of these springs when the end of the boom lies flat against the abutment 28. The size of the frictional force is in proportion to the pressure 25 from the springs 29 on the friction-plates, and also depends upon the condition of the friction surfaces whether dry, rusty or oily. The pressure from the springs will increase with increased friction, and will decrease with decreasing vertical distance 30 between the frictional force and the pressure of the boom on the abutment. The pressure from the springs must as shown above remain constant, therefore if the friction increases, say due to rust, the vertical distance 35 must automatically decrease as the center of the pressure on the abutment will move closer to the lower edge of the boom, and if the friction becomes small, say due to greasy 40 surfaces, the center of the pressure moves automatically closer to the upper edge of the boom. By this arrangement the brake-shoe is prevented from getting stuck due to too great friction.

45 Openings 20 in the side-arms of the brake-shoe are formed with a plurality of shoulders located in advance of each other, so that in normal or initial position the friction plates 18 will be positioned slightly in advance of each other with the uppermost plates near the rear end of the openings 20. Thus as the force is applied, the plates 18 will be picked up one after the other, thereby gradually increasing the frictional resistance 50 at the beginning of the backward movement.

In Fig. 1 the train-tracks are shown level 60 throughout their length, with their rear ends anchored in the bases of the piers, and in Fig. 3, the anchoring structure for the train-tracks and support for the operative parts of the device is modified to provide an anchoring means which will securely hold the ends of the tracks when they are turned upwardly. This latter construction is built

up of heavy beams of any suitable material and in any desired manner, and preferably provided with metal anchoring members 30 in which the ends of the rails are secured, either by wedging or otherwise.

70

In operation, with the parts in normal or initial position, as shown in Fig. 1, when the train strikes the buffer-end of the boom the force is transmitted by impact to the brake-shoe with the tendency of driving the 75 brake-shoe rearwardly and producing a tilting movement which is caused by the initial resistance means, viz., the springs 23, or their equivalent which might be a counter-weight. It is obvious that the tilting movement will force the frictional members together which will cause a drag in opposition to the moving body, and which in a short distance will overcome the pressure of the moving body and thereby gradually stop the 80 train.

85

As the brake-shoe starts to travel backwardly from the pressure applied, it engages the friction-plates 18 in succession, and thus increases the frictional resistance gradually 90 at the beginning of the rearward movement. After the train has been stopped and then withdrawn from engagement with the bumper, the initial resistance means 23 will then act to return the brake-shoe to its starting point and in position to receive another operating pressure. It is clearly obvious that the friction-plates are moved rearwardly by the front edges of the openings 20 engaging the heads 19, and forwardly or 100 back to normal position, by the rear edges or shoulders of the opening 20.

95

In the modification shown in Fig. 4, of the drawings, a sliding shoe 38 is provided to support the brake-shoe upon the supporting beam 5.

105

What is claimed is:—

1. In a train-bumper, a fixed supporting beam, a brake-shoe mounted on said beam to move back and forth thereon, separate 110 groups of friction members arranged in alternate relation to each other and mounted respectively fixed and movable with said brake-shoe, and a movable boom guided on said supporting beam and engaging the 115 brake-shoe intermediate the friction members and the top side of the brake-shoe.

2. In a train-bumper, a fixed supporting beam, a brake-shoe mounted on said beam to move back and forth thereon, separate 120 groups of friction members arranged in alternate relation to each other and mounted respectively fixed and movable with said brake-shoe, and a movable boom guided on said supporting beam and engaging the 125 brake-shoe intermediate the friction members and the top side of the brake-shoe, and an initial resistance means attached to the lower end of the brake-shoe.

3. In a train-bumper, a fixed supporting 130

- beam, a brake-shoe mounted on said beam to move back and forth thereon and constructed to straddle said supporting beam, separate groups of friction members arranged in alternate relation to each other and mounted respectively fixed and movable with said brake-shoe, and a movable boom guided on both sides of said supporting beam and engaging the brake-shoe intermediate the friction members and the top side of the brake-shoe. 5
4. In a train-bumper, a fixed supporting beam, a brake-shoe mounted on said beam to move back and forth thereon, said brake-shoe being provided at its upper end with a guide roller to travel on the top edge of the supporting beam and at its lower end with a resistance means operating to produce a tilting movement of the brake-shoe, 10 separate groups of friction members arranged in alternate relation to each other and mounted respectively fixed and movable with said brake-shoe, and a movable boom guided on said supporting beam and engaging the brake-shoe intermediate the friction members and the top side of the brake-shoe. 15
- 20
- 25
5. In a train-bumper, a fixed supporting beam, a brake-shoe mounted on said beam to move back and forth thereon, separate groups of friction members arranged in alternate relation to each other and mounted respectively fixed and movable with said brake-shoe, and a movable boom guided on said supporting beam and engaging the brake-shoe by impact intermediate the friction members and the top side of the brake-shoe. 30
- 35
- 40
- 45
- 50
6. In a train-bumper, a fixed supporting beam, a brake-shoe mounted on said beam to move back and forth thereon and constructed to straddle said supporting beam, separate groups of friction members arranged in alternate relation to each other and mounted respectively fixed and movable with said brake-shoe, said brake-shoe being formed with openings in its side arms to receive portions of the movable friction members, and said openings being formed with a plurality of advanced shoulders to position the movable friction members initially advanced relative to each other, and a movable boom guided on both sides of said supporting beam and engaging the 55
brake-shoe intermediate the friction members and the top side of the brake-shoe. 60
7. In a train-bumper, a fixed supporting beam, a brake-shoe mounted on said beam to move back and forth thereon and constructed to straddle said supporting beam and provided with abutments on its side arms, separate groups of friction members arranged in alternate relation to each other and mounted respectively fixed and movable with said brake-shoe, and a movable boom 65 guided on both sides of said supporting beam and engaging the abutments on the brake-shoe intermediate the friction members and the top side of the brake-shoe. 70
8. In a train-bumper, a fixed supporting beam, a brake-shoe mounted on said beam to move back and forth thereon and constructed to straddle said supporting beam, separate groups of friction members arranged in alternate relation to each other 75 and mounted respectively fixed and movable with said brake-shoe, and a movable boom guided on rollers pivoted on both sides of said supporting beam and engaging the brake-shoe intermediate the friction members and the top side of the brake-shoe. 80
9. In a train-bumper, a fixed supporting beam, a brake-shoe mounted on said beam to move back and forth thereon, separate groups of friction members arranged in alternate relation to each other and mounted respectively fixed and movable with the 85
brake-shoe, a movable boom guided on said supporting beam and engaging the brake-shoe above the friction members, and springs 90 adapted to be pressed against the friction members by the tilting of the brake-shoe when engaged by the boom. 95
10. In a train-bumper, a fixed supporting beam, a brake-shoe mounted on said beam to move back and forth thereon, separate groups of friction members arranged in alternate relation to each other and mounted respectively fixed and movable with the 100
brake-shoe, a movable boom guided on said supporting beam and engaging the brake-shoe above the friction members, and springs adapted to be pressed against the friction members with a constant pressure caused by a restricted tilting movement of the 105
brake-shoe when engaged by the boom. 110

In testimony whereof I affix my signature.
HOLGER VARDER.
